ELEVATING AND LOWERING MECHANISM FOR MAGAZINES OF CHARGING MACHINES

Filed June 25, 1927

UNITED STATES PATENT OFFICE

OLAV TWEIT, OF ORANGE, NEW JERSEY, ASSIGNOR TO SEMET-SOLVAY ENGINEERING CORPORATION, OF NEW YORK, N. Y., A CORPORATION OF NEW YORK

ELEVATING AND LOWERING MECHANISM FOR MAGAZINES OF CHARGING MACHINES

Application filed June 25, 1927. Serial No. 201,520.

This invention relates to a magazine elevating and lowering mechanism and particularly to a device for raising and lowering the magazine of a charging machine for gas generators with respect to the generator, together with the mechanism for holding the magazine in gas tight engagement with said generator.

In one type of charging machine as heretofore constructed, in order to permit the removal of the truck and magazine carried thereby from the generator, both the truck and magazine have been moved relatively to one another, the truck being elevated above its normal support so that it remains unsupported and the magazine being simultaneously moved downwardly into operative position on the generator. In this construction, the entire weight of the truck, magazine and the structure connected thereto is supported by the upper flange of the generator. Further, to provide a gas tight engagement between the magazine and the generator it has usually been necessary to bolt these two members together. This, of course involves considerable time, is a tedious operation and consequently increases the cost of the manipulation and operation of the charging device.

An object of my invention is to simplify charging machines as heretofore constructed and provide a magazine construction readily movable into and out of operative position, that is simple in construction and efficient in operation.

The invention accordingly comprises a magazine carried on a truck mounted to run on rails that is movable to and from operative position in combination with means to lower said magazine into engagement with the generator while maintaining the truck in its normal position on said rails.

Other objects and advantages will appear from the following detailed description taken in connection with the accompanying draw-

ings in which Fig. 1 is a fragmentary end elevation partly in section of a charging device in operative position, showing the truck and the magazine in charging position and illustrating an embodiment of the invention; Fig. 2 is a fragmentary side elevation of Fig. 1 partly broken away and Fig. 3 is a detail elevation partly in section of the cradle shown in Fig. 2.

In the preferred embodiment of the invention illustrated on the drawing, 1 indicates the generator of the usual gas producing machine, having a flange 2 supporting the casting 3. This casting has a plurality of lugs 4 integral with or fastened thereto in any suitable manner.

Tracks 5-5 are disposed at each side of the generator, and running thereon are the wheels 6 of the truck, comprising the channel bars 8, 8. Fastened preferably to each of the side channel bars by bolts 9 or other suitable means are supports or cradles 10, which extend away from the channel bars as indicated at 11, and are provided at the ends 12 with circular or U-shaped bearing portions 13. Each cradle 10 has bolted thereto as at 14 a detaining spring 15 the function of which will be hereinafter explained.

A magazine 16 is mounted on the truck adapted to move therewith. It is understood that in normal operation the magazine of the charging device is in gas tight engagement with the generator and remains thus positioned until it is desired to gain access to the generator or inspect the charging device, whereupon the magazine is disengaged from the generator and moved on the truck into position, where inspection of the charging device or generator may be had. In order to permit the ready removal of the charging device and to maintain it in gas tight engagement with the generator when in operative position, an elevating, lowering and clamping structure is preferably provided at each side of the magazine. It is understood, of course,

that any desired number of these clamping and moving devices may be used in conjunction with the magazine and truck.

In Fig. 1 shafts or rods 18 are shown fixed in bearings 19 integral with or fastened to each side of the magazine at 20. Bifurcated levers 21 are pivoted on these shafts 18 and their movement toward the magazine is limited by lugs 22 extending from the magazine. Mounted in the arms of levers 21 are the rods 23, these rods being so positioned that when the levers are swung about their pivots away from the magazine, they engage and rest in the circular or U-shaped bearing portions 13 of cradles 10. Pivoted on rods 23 are hooks or clamps 24 which have positioned thereon or integral therewith handles 25. A stop 31 is formed on the casting 3 and is adapted to contact with the hook 24 when in lowered position to properly register the magazine with respect to the generator opening. This can readily be accomplished by moving the magazine with the hooks 24 in lowered position into contact with this stop.

The upper extremities of levers 21 are secured to sleeves 26 frictionally engaging nut or circular members 26' which are in threaded engagement with the threaded rods 27 pivoted to lugs 28 extending from the magazine. Hand wheels 29 integral with or secured to the nut members are provided to readily manipulate levers 21. The nut members 26' have projections at the end peripheral edge adjacent the lugs 28, which projections engage the ends of sleeves 26. When the nut members are rotated by the hand wheels 29 they turn in the sleeves 26 which do not rotate with the nut members but move longitudinally of the rods 27.

In operation, assuming that the magazine has been moved over the generator as shown in dotted lines Fig. 1, and it is desired to lower it into gas tight engagement with said generator, hand wheels 29 are turned, gradually swinging the threaded rods 27 upwardly from the dotted to the full line positions, (Fig. 1) and simultaneously rocking the bifurcated levers 21 about shaft 18 until the levers engage lugs 22, whereupon continued movement of the levers causes a downward pressure to be exerted on the magazine, forcing it into engagement with the generator. Hooks 24, having been released from the detention spring 15 and moved into position beneath the lugs, are lifted upwardly by the movement of levers 21 until they engage the lugs 4, continued movement of the levers forcing the magazine down and causing an upward pressure to be exerted on the lugs 4 by the hooks 24 so that there results a gas tight engagement between the magazine and generator. It will be noted that throughout this operation the truck remains on the tracks and that only the dead weight of the

magazine rests on the generator, there being clearances 30 between the U-shaped bearing supports of the cradle and the rods 23 when the magazine and generator are in engagement.

To elevate the magazine, it is only necessary to turn the hand wheels in the opposite direction, whereupon the threaded rods are gradually moved to the dotted line positions, Fig. 1, and the bifurcated levers are rocked about shafts 18 until the clearances 30 between rods 23 and U-shaped bearing portions 13 are taken up. This movement is sufficient to move the hook 24 away from lugs 4, whereupon the hooks 24 are readily swung about rods 23 to move handles 25 into detaining springs 15 thus clearing stop 31 and permitting movement of the truck in either direction towards or away from stop 31. This can be accomplished by simply kicking the handle up into engagement with spring 15. Continued movement of levers 21 causes the U-shaped bearings and rods 23 to act as a fulcrum about which lever 21 is moved, elevating the magazine and supporting it on the truck in the U-shaped bearings 13. The charging device may then be readily moved into inspection position away from the generator.

It will be noted that the mechanism hereinbefore described is simple in construction, efficient in operation, provides a ready means for elevating and lowering the magazine while maintaining the truck in position on its supporting surface, and also provides a gas tight clamp between the magazine and generator that is readily applied and removed.

It will, of course, be understood that while a specific embodiment of the invention has been shown and described, various changes in the details thereof may be made by those skilled in the art, and the invention is not to be limited to the structure disclosed but only by the scope of the appended claims.

What is claimed is:

1. In a fuel charging machine, a generator having a charging opening, a truck movable with respect to said generator, a magazine carried by said truck adapted to engage the charging opening of the generator, a lever pivoted to said magazine and engaging a fulcrum on said truck, said magazine being supported on said truck by said lever and fulcrum, and means for operating said lever to position said magazine relatively to said truck.

2. In a fuel charging machine, a generator having a charging opening, a truck movable with respect to said generator, a magazine carried by said truck and adapted to engage the charging opening of the generator, a pair of levers each having one end pivoted to one side of said magazine and each engaging a fulcrum on said truck, said magazine being supported on said truck by

5 said levers and fulcrums, said levers having the other ends secured to sleeves rotatably mounted on nut members in threaded engagement with rods on said magazine and means for moving the said nut members to operate said levers to position said magazine relatively to said truck.

10 3. In a fuel charging machine, a generator, a truck, a magazine on said truck in engagement with said generator, a lever pivoted to the lower portion of the magazine and a cradle on said truck arranged to act as a fulcrum for said lever to elevate said magazine.

15 4. In a machine of the class described, a truck, a magazine on said truck, means pivoted on said magazine and adapted when moved in one direction to lower said magazine, and a supporting surface on said truck arranged 20 to engage said means to act as a fulcrum for elevating said magazine when said means are moved in another direction.

25 5. In a machine of the class described, a truck, a magazine carried by said truck, a lever pivotally mounted on the lower portion of said magazine, means for moving said lever to raise and lower said magazine, a rod mounted on said lever and a cradle on said truck arranged to engage said rod when said 30 lever is moved to raise said magazine.

35 6. In a machine of the class described, a truck, a magazine on said truck, levers pivoted on the opposite sides of the lower portion of said magazine, means for moving said levers to lower said magazine, rods mounted on said levers, and cradles on said truck on opposite sides thereof arranged to engage said rods to act as a fulcrum about which the magazine is raised.

40 7. In a fuel charging machine, a generator, a truck, a magazine on said truck arranged to be positioned in engagement with said generator, a threaded rod pivotally mounted on said magazine, a nut member in threaded engagement with said rod, a lever pivoted to the lower portion of the magazine and operatively connected to said nut member and a cradle on said truck arranged to act as a fulcrum for said lever to elevate said magazine when said lever is moved by said nut member.

45 8. In a fuel charging machine, a generator having a lug projecting therefrom, a magazine, a lever pivoted to the magazine, means for moving said lever to lower said magazine and means connected to said lever arranged to engage said lug to provide a tight engagement between said magazine and generator.

50 9. In a fuel charging machine, a generator having a lug projecting therefrom, a magazine, a lever pivoted to the magazine, means for moving said lever to lower said magazine, and a hook pivotally mounted on a rod on said lever arranged to engage said lug.

55 10. In a fuel charging machine, a gen-

erator having lugs projecting therefrom, a magazine, levers pivoted to the magazine, means for moving said levers to lower said magazine into engagement with said generator, rods mounted on said levers and hooks pivoted on said rods and adapted to engage 70 said lugs.

11. In a fuel charging machine, a generator having lugs projecting therefrom, a magazine, threaded rods pivotally connected to said magazine, hand wheels in threaded engagement with said rods, levers pivoted to the magazine and operatively connected to said hand wheels, and means connected to said levers arranged to engage said lugs 75 80 providing a clamp between said magazine and generator when the levers are moved by said hand wheels.

12. In a fuel charging machine, a generator having a lug projecting therefrom, a magazine, a lever pivoted to the lower portion of the magazine, a rod mounted on the lever, a hook pivoted on said rod and arranged to engage said lug, and means to move said lever to lower the magazine and elevate the hook, forming a tight engagement between said magazine and generator. 85 90

13. In a fuel charging machine, a generator having lugs projecting therefrom, a magazine, bifurcated levers pivoted to the lower portion of said magazine, rods mounted on the levers, hooks pivoted on said rods and arranged to engage said lugs and means to move said levers to lower the magazine and simultaneously raise the hooks, thus 95 100 clamping said magazine on to the generator.

14. In a fuel charging machine, a generator having lugs projecting therefrom, a truck, a magazine on said truck, a stop on said generator arranged to act as a registering means for said magazine when said truck is moved into operative position, a lever pivoted to the lower portion of the magazine, a rod carried in the arms of the lever, a hook provided with a handle pivoted on said rod and arranged to engage said lug, a cradle on said truck adapted to act as a fulcrum for said lever about which said magazine is elevated and a spring on the cradle arranged to engage the handle and retain the hook in inoperative position to clear said stop. 105 110 115

15. In a machine of the class described, a generator having a casting mounted thereon, lugs on said casting, a truck, a magazine carried by the truck, supporting lugs on the magazine, screw threaded rods pivotally mounted on said supporting lugs, hand wheels having nut members integral therewith in threaded engagement with said rods, levers provided with bifurcated ends fastened to said nut members and pivotally mounted on a shaft carried by the magazine, rods carried by the lower bifurcated ends of said levers, hook members pivotally mounted on said latter rods provided with 120 125 130

handles and adapted to engage the lugs on
said casting, cradles fastened to the truck
and having U-shaped bearing members
adapted to receive said latter rods and pro-
vide a fulcrum for said levers, and spring
holding members on said cradles arranged
to receive the handles of the hooks to retain
them in elevated position.

In witness whereof, I have hereunto set
my hand.

OLAV TWEIT.
